Primary Examiner — Michelle E. Wilson*Assistant Examiner* — Amanda J Berlinski(74) *Attorney, Agent, or Firm* — Oliff PLC(57) **CLAIM**

The ornamental design for a swallowing sensor, as shown and described.

DESCRIPTION

FIG. 1 is a front, right-side, and top perspective view of the swallowing sensor, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

1 Claim, 5 Drawing Sheets(56)
